UNITED STATES PATENT OFFICE.

CASPAR METTLER, OF NEW HAVEN, AND RAYMOND E. FUDGE, OF WEST HAVEN, CONNECTICUT, ASSIGNORS TO J. FREDERICK SCHERMOND, TRUSTEE, OF NEW HAVEN, CONNECTICUT.

VENDING-MACHINE.

1,082,817.

Specification of Letters Patent. Patented Dec. 30, 1913.

Application filed July 20, 1911. Serial No. 639,559.

To all whom it may concern:

Be it known that we, CASPAR METTLER, a citizen of the United States, residing at New Haven, in the county of New Haven and State of Connecticut, and RAYMOND E. FUDGE, a citizen of the United States, residing at West Haven, town of Orange, in said county and State, have invented certain new and useful Improvements in Vending-Machines, of which the following is a specification, reference being had therein to the accompanying drawings.

Our invention relates to new and useful improvements in vending machines for articles of irregular shape, such as loaves of bread, etc., and has for its object, among other things, to construct such machine of few parts that are automatic in their operation, and so designed as to be economically constructed and assembled.

To these, and other ends, our invention consists in the vending machine, having certain details of construction, and combinations of parts, as will be hereinafter described and more particularly pointed out in the claims.

Referring to the drawings, in which like numerals of reference designate like parts in the several figures: Figure 1 is a side elevation of our improved machine with the door partially removed, for the purpose of exhibiting the interior mechanism; Fig. 2 is a front elevation thereof, partly in section; Fig. 3 is a detailed view of the carrier; Fig. 4 is a view of the upper sprocket wheel with the mechanism adjacent thereto; Fig. 5 is a view of the parts shown in Fig. 4, looking toward the left of said figure; Fig. 6 is a view of the lower sprocket wheel with the mechanism adjacent thereto; Fig. 7 is a view thereof looking toward the left of Fig. 6; Fig. 8 is a view of the pawl disk; Fig. 9 is a view of the coin mechanism; and Fig. 10 is a view thereof looking toward the left of Fig. 9, with the money box and frame in section.

In the practice of our invention the mechanism is contained within a case 1, that is supported upon a standard 2, fixed in any convenient manner to a base 3, the case 1 having parallel sides with curved upper and lower portions, as shown in Fig. 1. One side of this case is closed by a hinged door 4, and upon the inside of the case, opposite

the door, is the retaining plate 5, to which 55 the brackets 6 and 7 are fixed, and within which is rotatably mounted the shafts 8 and 9. Upon the shaft 8 are fixed the sprocket wheels 10 and 11, said latter wheel having laterally projecting pins 45 fixed therein, 60 and upon the shaft 9 are fixed the sprocket wheels 12 and 13, said sprocket wheel 12 having the laterally projecting pin 48 therein, all the sprocket wheels being of the same diameter. Connected with said 65 sprocket wheels in the usual manner, is the sprocket chain 14, to which are affixed a plurality of carriers 15, preferably, but not necessarily, made of a single piece of sheet metal, and formed so as to have base portions 16, upon which are the retaining fingers 17, and upon one side thereof is the plate 18 to prevent endwise shifting of the contents of the carrier in one direction. We prefer to have the plate 18 upon only one 75 end of the carrier, but it can be constructed on both ends if desired. While we have shown the preferred form of carrier, it is obvious that any form may be substituted to accommodate the article to be contained 80 therein.

Upon one side of the case 1 is fixed a journal collar 19, within which is rotatable the shank 20 of the lever 21. Fixed upon said shank, within the interior of the case, by 85 the pin 22, is the coin disk 23, having a pin 24 fixed therein, projecting laterally therefrom over the edge of the coin wheel 25, loosely mounted upon the hub of the disk 23, between said disk and the collar 26. In 90 the edge of this disk is a coin slot 27, and projecting radially from one edge thereof, is a lug 28 that lies between the stop pin 29 fixed in the plate 5 and the said pin 24 when the parts are in position to receive a coin. 95 Projecting across the slot 27, in the wheel 25, are the coin pins 36, that are so spaced in relation to each other that the coin of proper denomination will not pass therebetween. Fixed to the lever 21 is a pin 30 that limits 100 the movement thereof when said pin contacts with the studs 31 and 32 fixed in the journal collar 19. Surrounding the enlarged portion of the shank 20 of the lever 21, is the coil spring 33, one end of which is 105 fixed to the lever 21, and the other end connected with either one of the studs 31 and 32, the action of said spring being such that

it retains the coin disk 23 and coin wheel 25 in the position shown in Figs. 1 and 9, that is, ready to receive a coin.

The numeral 34 designates the coin chute, which is secured so as to incline downwardly from the coin slot 35, in the case 1, to the point where it delivers the coin into the slot 27, the coin channel in said chute being only large enough to admit a coin of proper 10 nomination.

Attached to the plate 5, below the coin wheel 25, is a coin box 37, which is closed at one end by the cover 38, and provided with a slot 39 therein, that is, opposite the slot 27, and through which the coins fall from the coin wheel. Pivotal secured to the plate 5 by the screw 40 is a locking bar 41, having a notch 42 near its upper end, in the path of the pins 45, and a lug 43 upon one side thereof adjacent to the coin wheel 25, the upper end of the locking bar 41 being steadied by the fixed plate 44. The retaining latch 46 is pivotally secured to the plate 44, and is provided with a notch 47 in one edge thereof that lies also in the path of the pins 45.

Rotatably mounted upon the hub of the sprocket wheel 12 is the pawl disk 49, having a pawl 50 pivotally connected therewith by the screw 51, and normally held by the spring 52, with its outer end in the path of the pins 48. A link 53 joins the coin wheel 25 with the pawl disk 49 and forms an operative connection therebetween.

At the lower end of the case 1 is a discharge opening 55, that is closed by a hinged door 56, and leading therefrom is a discharge chute 54. The door 56 is locked, when in its closed position, by the locking bar 57, pivotally mounted upon the screw 58, with its upper end in the path of a pin 59 in the pawl disk 49, and the lower end of which is provided with a laterally projecting pin 60 that passes under the retaining hook 61 fixed to the door 56, as shown in Fig. 1. As the pin 59, during its rotation, strokes the end of the locking bar 57, it imparts a rocking movement thereto and moves the pin 60 from its engagement with the hook 61 and permits the door 56 to drop by gravity. Secured to the pawl disk 49, by the pintle 63, is the lever 62, that slides against one side of the fixed pin 64, and has a laterally projecting lip 65 upon the lower end thereof, that projects under one edge of the door 56, as shown in Fig. 2. The rotation of the disk 49, with a coin in the coin wheel, moves the lever 62 from the position shown in full lines, in Fig. 1, to that shown by dotted lines, so that when the door is released by the actuation of the lever 57, it will open by gravity, assisted by the weight of the package delivered thereon from the carrier, and the return movement of the pawl disk 49 draws the lever 62 upwardly

and the door is raised to its closed position by the contact of the lip 65 with the underside thereof, and when in its closed position the pin 60 will drop under the hook 61.

We have provided a mechanism for disclosing the fact that the machine is empty, and preventing the insertion of a coin in the chute under such circumstances. This device consists of a rock lever 66, having a downwardly projecting arm 67 thereon and 75 an upwardly projecting arm 68, a plate 69, one face of which is exposed through an opening 70 in the case, that is connected with the arm 68 by the link 71, and a pad 73 upon one end of a rod 72 that is fixed to 80 the link 71.

When the machine is loaded, the parts are in the relative positions, substantially as shown, in Fig. 1, with the lower end of the arm 67 held in contact with the contents 85 of the lower carrier 74 by the spring 75, in which position the pad 73 is out of the path of the coin chute, and the plate 69 is in its down position so as not to be readily observed through the opening 70. After the carrier 74 has passed the end of the arm 67 and brought into its discharge position under the sprocket wheels, the spring 75 pulls the link 71 and rock arm 66 upwardly, and the plate 69 is brought to its position 90 adjacent to the side of the case, and through which the word "empty," or similar phrase, can be readily seen. At the same time, the pad 73 is moved up so as to close the open end of the coin chute, thus preventing the 100 admission of a coin therein.

In operation, the coin rolls through the coin chute from the opening 70, and drops into the slot 27 of the coin wheel, contacting with the pins 36, as shown in Fig. 9, by 105 broken lines. The operator now grasps the lever 21 and moves it about its pivot mounting, at which time the pin 24 contacts with the coin, thereby making a rigid connection between the coin disk, coin wheel, and the coin itself, so that movement of said lever is imparted to the coin wheel. During the first portion of the coin disk rotation, the outer edge of the coin contacts with the lug 43 on the locking bar 41, moving said 110 locking bar against the tension of the spring 76 to the position shown by broken lines in Fig. 4, wherein the notch 42 is out of the path of the pins 45. At this time the pawl disk 49 is rotated through the link 53, and the pawl 50 thereon rotates the sprocket wheel 12 through its contact with one of the pins 48. This movement is transmitted through the sprocket wheels and shafts 8 and 9 to the sprocket chain 14, and the carriers are advanced one step. These steps successively bringing the several carriers into register with the opening 55 in the bottom of the case, at which time the pin 30 in the lever 21 contacts with the stud 115 12

31 13

in the collar 19. As the entire movement of the lever 21, above described, is against the tension of the spring 33, it is immediately returned to its original position when released. The return movement of the pawl disk 49 actuates the levers 57 and 62 so as to close and lock the door 56, as above described. A spring 77, fixed to one side of the coin box 37, strips the coin from the coin wheel, during the return movement of said coin wheel, if perchance it does not drop by gravity into the coin box. A return movement of the sprocket chain is also prevented by the retaining latch 46, the notch 47 therefore engaging with one of the pins 45 at the completion of each successive advance movement of the sprocket chain. A return movement of the coin wheel and disk is limited by the stop 29, as shown in Fig. 10, in which position that portion of the slot 27 between the pins 36 is again in register with the coin chute.

The device cannot be operated by a coin of any other denomination than that for which the machine is arranged, for if of larger diameter it will not enter the chute, and if smaller it will pass between the pins 36, through the coin wheel 27 and slot 39 into the coin box, without operating the machine.

The door 56 is in its open position when each of the carriers registers therewith, so that the contents drop therefrom by gravity through the opening 25 into the chute 54, from which they are readily removed.

When the device is used for vending bread, the same is usually wrapped in paper before being placed in the machine, and thus a double precaution is taken to keep the bread sanitary, and being inclosed within an outer case, the bread retains its flavor and freshness a much longer time than if kept in the open.

There are minor changes and alterations that can be made within our invention, aside from those herein suggested, and we would therefore have it understood that we do not limit ourselves to the exact construction herein shown and described, but claim all that falls fairly within the spirit and scope of our invention.

Having described our invention, what we claim as new and desire to secure by Letters Patent, is:—

1. A machine of the class described comprising a swinging delivery door, a pivoted lock releasably engaging the door for holding it in receiving position, means for delivering articles to the door, means for releasing the latch when an article is delivered to the door for permitting the latter to drop to discharging position, and means for automatically raising the door after the article is discharged for engaging the lock with the door.

2. The combination of an article-carrying mechanism having an oscillatory element movable step by step, a door for receiving an article upon each step of the mechanism, a lock for holding the door in receiving position and arranged to be released by the said oscillatory element whereby the door and article thereon move to discharging position, and means connected with the element for returning the door to a position for engagement by the said lock. 70 75

3. A vending machine comprising an endless element, a plurality of article carriers thereon, a shutter or delivery door upon which each carrier deposits an article, means for moving the said carrier element, an automatically-set lock normally holding the door in receiving position and arranged to be released by the said means after a carrier deposits an article on the door to permit the door to move to delivery position, and an element connected with the said means for moving the door from delivery to receiving position. 80 85

4. A machine of the class described comprising an endless carrying mechanism movable step by step, an element having a back and forth movement with each step of the mechanism, a pawl and ratchet device for producing step by step movement in one direction of the said mechanism, a device cooperating with the said mechanism for receiving therefrom and carrying articles to be dispensed, and means controlling the movement of the device to and from discharging position by the movement of the said element. 90 95 100

5. A machine of the class described comprising a carrying mechanism, means for moving the same, a door mounted to receive articles from the said mechanism, a catch on the door, a pivoted lock mounted to automatically engage the catch when the door is moved to receiving position, means for operating the lock to release the catch 105 110 115 for permitting the door to move to discharging position, and a longitudinally-movable element for engaging the door to move the same from discharging to receiving position.

6. The combination of a door for receiving an article to be discharged, means for depositing articles thereon, a lock for holding the door in receiving position, an oscillatory element arranged to engage and release the lock after an article is placed on the door, and a door-engaging rod pivotally connected with the element and movable longitudinally thereby for returning the door from discharging to receiving position. 120 125

7. The combination of a manually-operated oscillatory device, an oscillatory element, a link connection between the device and element for operating the latter by the former, a carrier mechanism moved step by 130

4
step by the said element, an article delivering door coöperating with the mechanism, and means operated by the said element for controlling the opening and closing of the

5 door.

8. A machine of the class described comprising an endless element, carriers mounted thereon, spaced shafts, wheels on the shafts for guiding the element and driving

10 the same, an oscillatory device, a ratchet and pawl means between the device and one of the shafts for positively rotating the latter, a manually-operated element located between the shafts, and a link connection between

15 the manually operated element and said device.

9. A machine of the class described comprising an endless element, carriers mounted thereon, wheels for guiding the element and driving the same, an oscillatory device, a ratchet and pawl means between the device and one of the wheels for positively rotating the latter, a manually-operated element, a link connection between the element and

25 said device, a door controlling the discharge of articles from the carriers, and means operated by the said device to control the opening and closing of the door.

10. A machine of the class described comprising an endless element, a rotary driving

means therefor movable step by step, an oscillatory element associated with the driving means, a ratchet and pawl between the oscillatory element and driving means, an oscillatory element moved manually in one 35 direction, means for moving the last-mentioned element in the opposite direction, and a link connection between the two oscillatory elements for simultaneous movement.

11. A machine of the class described comprising an endless element, upper and lower guiding means therefor, an oscillatory element, a pawl and ratchet connection between the element and one of the said means, an oscillatory element located between the guiding means, a connection between the oscillatory elements for simultaneous movement, a handle connected with the last-mentioned oscillatory element for moving the same in one direction, and a spring for moving the 50 handle and said element in the opposite direction.

In testimony whereof we affix our signatures in presence of two witnesses.
